UNITED STATES PATENT OFFICE.

LAVINOUS LALONE, OF WORCESTER, MASSACHUSETTS, ASSIGNOR TO HOBBS MANUFACTURING COMPANY, OF WORCESTER, MASSACHUSETTS, A CORPORATION OF MASSACHUSETTS.

WASTE REMOVER FOR CUTTING MACHINES.

Application filed January 29, 1923. Serial No. 615,715.

To all whom it may concern:

Be it known that I, LAVINOUS LALONE, a citizen of the United States, residing at Worcester, in the county of Worcester and 5 Commonwealth of Massachusetts, have invented a new and useful Improvement in a Waste Remover for Cutting Machines, of which the following, together with the accompanying drawings, is a specification.

10 My invention relates to machines for cutting, slitting or scoring a sheet of material and at the same time trimming the longitudinal edges thereof, as the material is acted upon by the cutting or scoring devices.

The object of my invention is to provide an improved device, whereby the waste material which is removed from along the longitudinal edges of the sheet, will be deflected 15 away from the line of movement of the sheet as it passes through the machine, and will be discharged from the machine, thereby effectually preventing any accumulation of waste material which might interfere with 20 the operation of the machine.

In the accompanying drawings,

Figure 1 is a view in front elevation of a portion of a machine embodying my invention.

30 Figure 2 is a view in side elevation of the parts shown in Fig. 1.

Figure 3 is an enlarged view in front elevation, showing my improved waste deflector removed from the machine.

35 Figure 4 is a view in side elevation of the deflector shown in Fig. 3.

Like reference characters refer to like parts in the different figures.

Referring to Figs. 1 and 2, the machine 40 generally comprises a frame 1, upon which is rotatably mounted a cylinder 2, adapted to be rotatably driven from a suitable source of power, not shown. The frame 1 supports a table 3, with the top surface of which the 45 periphery of the cylinder 2 is substantially flush. A cutter bar 4 extends across the machine above the cylinder 2 and a cutting disk 5 is arranged on the bar 4, so as to coat with the cylinder 2 and trim the edge of a 50 sheet of material passing between the disk 5 and the cylinder 2. Other cutting or scoring devices 6 are carried on the bar 4, the exact form and arrangement of the devices 6 forming no part of the present invention.

A waste remover 7 is mounted on a portion of the frame 1 beyond the end of the cylinder 2, and as best shown in Figs. 3 and 4, comprises a bracket 8 provided with an upwardly curved flange 9 having a slightly greater radius of curvature than the cylinder 2. The flange 9 terminates in a straight portion 10 which extends upwardly in the direction of the table 3 and is tangent to the surface of the cylinder 2. An arm 11 is pivotally supported on the 55 bracket 8 by a stud 12, and carries at its end a roll 13 rotatably mounted on a pin 14. The roll 13 is maintained in the direction of the cylinder 2 by means of a spring 15 connected at its ends to the arm 11 and to the bracket 8.

An adjusting screw 16 passes through the arm 11 with its projecting end abutting a lug 17 provided on the bracket 8. The spring 15 tends to hold the end of the screw 16 in engagement with the lug 17 and a lock nut 18 coacts with the screw 16 to lock the screw in position so as to maintain the periphery of the roll 13 away from the cylinder 2, a distance substantially equal to the thickness of the material to be passed through the machine.

When the machine described above is in operation, a sheet of material, which it is desired to trim, is passed between the cylinder 2 and the cutter 5, which removes a strip of waste material from the edge of the sheet. In passing between the cutter 5 and the cylinder 2, the sheet is also operated upon by the scoring or cutting devices 6, 85 if desired. As the trimmed sheet emerges from between the cutter 5 and the cylinder 2, it passes on to the table 3 which supports it horizontally, but the strip of waste material being unsupported, falls to one side 90 of the table 3. In order to further direct the waste strip to the waste remover 7, a deflector 19 is provided which turns the waste strip downwardly into engagement with the straight portion 10 of the flange 9, 100 which deflects the strip downwardly between the curved portion 9 and the cylinder 2. The waste strip is thus directed between the roll 13 and the cylinder 2, from between which the strip emerges in a direction opposite to that of the trimmed sheet on the table 3. In this way the waste material resulting from the trimming of a sheet 105

in the machine, is positively removed from the machine and deposited on the floor from which it may be readily gathered up and carried away.

5 It is apparent that my improved waste removing device is extremely effective in operation, for the reason that the upwardly extending portion 10 of the flange 9 intercepts the waste strips just as they are severed by the cutter 5, thereby substantially eliminating all possibility of the waste material piling up on the table 3, from where it would be extremely difficult to remove, and where a continued accumulation of 10 waste material would ultimately interfere with proper operation of the machine. My device is capable of ready adjustment to handle waste material of different thicknesses, for the roll 13 may be closely adjusted by means of the set screw 16 to always bring sufficient pressure to bear on the waste material to cause it to be discharged from the machine without jamming.

20 While I have shown my invention as applied to a particular arrangement of parts of a cutting or trimming machine, it is not so limited, but is susceptible of application to other similar machines without departing from the spirit and scope of my invention. I desire, therefore, that only such limitation be imposed thereon as may come within the scope of the appended claims.

I claim,

25 1. In a machine of the class described, the combination with a rotating cylinder for moving a sheet of material and a cutting device adapted to trim one edge of said sheet, of a waste remover comprising a deflector and a roll in frictional engagement 30 with said cylinder.

40 2. In a machine of the class described, the combination with a rotating cylinder for moving a sheet of material and a cutting device adapted to trim one edge of said sheet, of a waste remover comprising a member 45 adapted to deflect the waste strip from the sheet and a roll in frictional engagement

with said cylinder for discharging the waste strip from the machine.

3. In a machine of the class described, 50 the combination with a rotating cylinder for moving a sheet of material and a device adapted to trim one edge of said sheet, of a waste remover comprising a member curved around said cylinder, and an auxiliary roll 55 to engage the waste in conjunction with said cylinder.

4. In a machine of the class described, the combination with a rotating cylinder for 60 moving a sheet of material and a device adapted to trim one edge of said sheet, of a waste remover comprising a member curved around said cylinder, and a deflecting member to direct the waste downward.

5. In a machine of the class described, the 65 combination with a rotating cylinder for moving a sheet of material and a device adapted to trim one edge of said sheet, of a waste remover comprising a member curved around said cylinder, a deflecting 70 member to direct the waste downward, and an auxiliary roll to engage the waste in conjunction with said cylinder.

6. In a machine of the class described, the 75 combination with a rotating cylinder for moving a sheet of material and a device adapted to trim one edge of said sheet, of a waste remover comprising a deflecting member, a curved trough member, a roll to engage the waste in conjunction with 80 said cylinder, and spring means connecting said roll to the curved trough member.

7. In a machine of the class described, the 85 combination with a rotating cylinder for moving a sheet of material and a device adapted to trim one edge of said sheet, of a waste remover comprising a downward deflecting member, a trough member, a roll to engage the waste in conjunction with 90 said cylinder, and adjusting means to adjust the pressure of said roll against said cylinder.

Dated this 24th day of January, 1923.

LAVINOUS LALONE.
